UNITED STATES PATENT OFFICE.

ORRELL ASHTON, DECEASED, LATE OF SWAMPSMOTT, MASSACHUSETTS, BY HANNAH ASHTON, EXECUTRIX, OF SWAMPSMOTT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

RELASTING-MACHINE.

1,313,935.

Specification of Letters Patent. Patented Aug. 26, 1919.

Application filed February 15, 1916. Serial No. 78,519.

To all whom it may concern:

Be it known that ORRELL ASHTON, deceased, late of Swampscott, in the county of Essex and State of Massachusetts, invented certain Improvements in Relasting-Machines, of which the following description, in connection with the accompanying drawings, is a specification, like reference characters on the drawings indicating like parts

10 in the several figures.

This invention relates to machines generally known as relasting machines for use in inserting lasts in shoes. Such machines are of particular utility in the manufacture of 15 turn shoes, and the invention is accordingly illustrated and described herein with reference to such use; but it should be understood that the invention is not thus limited in its applicability since a machine in which many 20 of the novel features of the invention are embodied may be used with advantage for inserting lasts in shoes of other types such, for example, as stitchdown shoes.

In the manufacture of turn shoes the shoe 25 is first lasted and the upper attached to the sole with the parts wrong side out, after which the last is removed and the shoe is turned to position the parts right side out. A last is then again inserted in the shoe 30 preparatory to subsequent operations on the shoe. Although in lasting the shoe the upper is conformed as closely as possible to the shape of the last, the upper and also the sole after the shoe is turned present various 35 irregularities of contour which make it necessary to accomplish much of the shaping of the shoe after the shoe has been turned. It is the practice, therefore, to subject the various portions of the turned shoe to pounding 40 and ironing operations in order to conform the shoe to the shape of the last.

Since the final shape of the shoe therefore 45 is determined by the last which is inserted after the shoe is turned, it is important in good shoemaking that this last fit closely 50 within all portions of the shoe and even have a tendency to distend the shoe. For this reason the operation of mounting a turned shoe upon its last, as heretofore carried out, has been a difficult and laborious one. A particular difficulty has been encountered in forcing the forepart of the last

into the toe of the shoe. Although machines have been proposed for use in performing this operation on turn shoes, no such 55 machine, as far as I am aware, has been of sufficient practical utility heretofore to warrant its general use. It is the general practice, therefore, in relasting turn shoes to insert the forepart of the last loosely in the 60 shoe, grasp the shoe about the forepart, and while holding the shoe in this manner, strike the rear end of the last forcibly upon a block. In addition to the slowness and 65 laboriousness of the operation as thus carried out, the rear end of the last soon becomes battered by the blows upon the block so as to change its shape, and in consequence lasts frequently have to be discarded.

It is an important object of this invention to avoid the damage to lasts above referred to, and to provide a machine whereby the relasting operation, particularly as related to the insertion of the forepart of the last in the shoe, may be performed easily 70 and quickly without injury either to the last or to the shoe. To this end the invention provides a novel construction and organization of mechanism for effecting relative movement of a last and a shoe to cause the 75 last to be inserted in the shoe, and features of the invention are to be recognized in the general organization of the machine.

A further particular feature of the invention consists in a construction and arrangement whereby shoe engaging means is rendered effective to grip the shoe upon the operation of means for effecting relative movement of the last and the shoe. In the construction herein shown, which comprises 80 means for gripping the rear end of the sole of the shoe to restrain the shoe from forward movement, the gripping means is rendered effective to hold the shoe through the 85 operation of means which forces the last 90 into the shoe.

Another feature of the invention consists in the provision of novel means permitting relative adjustment of different portions of the mechanism to be effected for the purpose 100 of avoiding lost motion and increasing the effectiveness of the mechanism in its operation upon the work.

The above and other features of the in-

vention, including certain details of construction and combinations of parts, will now be described with reference to the accompanying drawings and pointed out in 5 the claims.

In the drawings:—

Figure 1 is a view in side elevation of a machine in which the invention is embodied,

Fig. 2 is a view similar to Fig. 1 of the 10 upper portion of the mechanism as modified for use with shoes having sewed heel seats,

Fig. 3 shows a portion of the mechanism as viewed from the opposite side of Figs. 1 and 2, and

Fig. 4 is a perspective view of the shoe support, with portions broken away.

The machine includes a standard 2 upon which is mounted a head 4 which serves to support the principal operative portions of 20 the machine at a height convenient for use by the operator. The head 4 is formed at one side to provide a flat table 6 upon which is mounted a shoe support comprising a plate 8 and a pad 10. The plate 8 is pivoted

25 to the table 6 at 12 and is permitted to swing about its pivot within limits determined by a slot 14 in the plate and a pin 16 on the table in order to permit the shoe support to adjust itself transversely to the

30 shape and position of the shoe, whether the shoe be a right or a left. The pad 10 is preferably formed of some slightly yielding substance such as rubber so as to avoid injury to the surface of the sole of the shoe, 35 and is secured to the plate 8 in any convenient manner, as by compressing it between the opposite end flanges of the plate. The pad 10, as shown in Fig. 4, is curved upon its supporting surface both longitudinally and transversely in substantial conformity to the required shape of the sole of the finished shoe, particularly at the shank; and as thus formed the pad not only avoids 40 injury to the surface of the sole, but when pressure is applied to the shoe in the manner to be subsequently described, the pad 45 serves to mold and shape the sole.

Sloping downwardly from the rear end of the table 6, and preferably formed as a 50 part of the head 4, is a bracket 18 projecting from the upper surface of which are a pair of pins 20 and 22 having sharp points at their upper ends for engagement with the lower surface of the rear or heel seat portion of the sole. These pins are threaded at each end for engagement with the bracket, and are similarly pointed at both ends to permit them to be reversed end for end when the points at one end have become 55 dull. Slots in the ends of the pins permit them to be turned to the proper position and to be adjusted as required by the use of a screw driver, and set screws 23 serve by engagement with the intermediate portions 60 of the pins to retain them in adjusted posi-

tion. Each of the pins 20 and 22 constitutes one of a pair of coöperating gripping jaws arranged for engagement with the sole to restrain the shoe from forward movement during the operation of inserting the last 70 in the shoe. The jaw complementary to the pin 20 comprises a member 24, Fig. 1, provided preferably with a smooth surface for engagement opposite to the teeth of the pin 20 with the upper surface of the 75 sole of a shoe which is made with a nailed heel seat, the sole of such a shoe being left free from attachment to the upper at the heel portion until after the relasting operation. The member 24 is pivoted to 80 the head 4 at 26 and is operated and controlled in a manner which will be subsequently described. As preferably formed it is provided, as shown, with a shoulder 27 for engagement with the rear end of the 85 sole to position the sole and the shoe in proper relation to the machine.

The illustrated machine comprises means for engaging the rear end of a last loosely inserted in a shoe on the supporting pad 10 90 and forcing the last forwardly into the toe portion of the shoe while the shoe is restrained from forward movement. The means for forcing the last into the shoe comprises a bell-crank lever 28 pivoted to the 95 head 4 at 30 and having a forwardly extending arm connected by means of a rod 32 to a treadle lever 34 which is pivoted to the standard 2 at 36, and an upwardly extending arm provided at its upper end with a bearing 38 in which a pusher rod 40 is longitudinally slidable toward or from the last. This rod has a forked end 42 presenting diverging surfaces for engagement with the rear end of the last on opposite sides, so as 100 to cause the last by wedging engagement with said surfaces to be steadied in its forward movement, and a handle end 44 whereby the rod may be pushed forwardly into engagement with the last. The rod 40 is 110 slotted longitudinally on its upper side to receive the end of a pin 46 on the bearing 38, whereby the rod is prevented from turning; and mounted in the slot in the rod is a spring 48 which engages at one end with the 115 pin and at the other end with a screw at the rear end of the rod so as to force the rod normally to its rearward limit of movement determined by the engagement of the forked end 42 with the bearing 38. On its lower 120 side the rod 40 is provided with ratchet teeth 50, and mounted to turn in a bearing in the lever 28 below the bearing 38 is a pin 52 to one end of which is secured a pawl 54 in position to engage the teeth 50 and retain 125 the rod 40 in different advanced positions with reference to the lever. Secured to the opposite end of the pin 52 is a crank 58 provided with a pin 60 arranged to engage in a slot in one end of a lever 62 fulcrumed on a 130

pin 64 on the lever 28. A spring 56 connected at its opposite ends to pins projecting respectively from the hub portions of the crank 58 and the lever 62 tends to swing the crank and the lever in directions to cause the pawl 54 to engage the teeth 50. Pivottally connected to the other end of the lever 62 is a rod 66 arranged to slide longitudinally in a bearing formed in a lug 68 on the head 4 and having secured thereon a collar 70 in position to engage the lug and thus limit the movement of the rod in one direction. The position of the collar 70 is such that it engages the lug 68 and stops longitudinal movement of the rod 66 before the lever 28 has arrived at its limit of rearward movement determined by a stop 72 on the standard 2 in the path of the treadle 34. Continued rearward movement of the lever 28 will thus cause the lever 62, by reason of its connection with the rod 66, to swing about its fulcrum 64 and operate the crank 58 to withdraw the pawl 54 from engagement with the teeth 50, thus releasing the rod 40 and permitting the spring 48 to slide the rod to its limit of rearward movement in the bearing 38. While the lever 28 is in its idle position determined by the engagement of the treadle 34 with the stop 72 under the influence of the spring 74, the rod 40 will therefore be retracted so as to permit a shoe to be mounted in position and a last to be loosely inserted in the shoe without interference from the pusher rod. At the beginning of the forward or operative movement of the lever 28, however, the reverse movement of the crank 58 and the lever 62 under the influence of the spring 56 will cause the pawl to engage immediately with the teeth 50, so that as the rod 40 is pushed forward by hand into engagement with the last it will be retained effectively in its advanced position. This arrangement serves to avoid lost motion in the operation of the treadle 34 and the lever 28, and renders the device effective to push the last at the beginning of its operative movement. After the last has been partially forced into the shoe, moreover, the treadle and the lever 28 may be retracted relatively to the rod 40 to permit the pawl 54 to engage the teeth 50 farther from the last, after which the treadle and the lever may be operated again to effect the final forward movement of the last. Such retraction of the lever causes the member 42 to engage the last nearer the top of the heel portion and permits more effective leverage to be obtained during the final movement of the last into the shoe.

60 The gripping of the rear end of the sole between the movable jaw 24 and the pin 20 to restrain the shoe from forward movement is effected through the operative movement of the lever 28. To this end the lever carries a roll 76 and the member 24 has an arm

78 extending rearwardly into position to be engaged by the roll. The arm 78 is cut away at its rear end, as shown at 80, so that as the lever 28 approaches its idle position the arm 78 may swing downward under the influence of gravity and thus open the jaw 24. As the lever begins its forward or operative movement, the pin 76 encounters the portion 82 of the arm 78 and closes the jaw 24 upon the sole. It will be noted, moreover, that the position of the roll 76 with reference to the axis of movement of the lever 28 is such that as the lever continues its operative movement after having closed the jaw 24 it causes the jaws to grip the sole with constantly increasing pressure. The resistance to forward movement of the shoe is thus increased in proportion to the increase of pressure upon the rear end of the last.

It will be understood that when the parts of the machine as thus far described are in their idle positions the upwardly extending arm of the lever 28 is at its limit of rearward movement determined by the stop 72 in engagement with the treadle 34, and that the rod 40 is at its limit of rearward movement in the bearing 38 because of the fact that the pawl 54 is held by the mechanism hereinbefore described out of position to engage the teeth 50. While the lever 28 is thus retracted, the roll 76 is beneath the reduced end portion 80 of the arm 78 and this arm by its weight maintains the member 24 in upraised position with reference to the pin 20. A turn shoe of the type which is made with a nailed heel seat is now positioned upon the pad 10 with the rear end of the sole projecting over the pin 20 and engaging the shoulder 27 of the member 24, and a last is pushed by hand part way into the forepart of the shoe. Such partial insertion of the last in the shoe may be effected, if desired, before the shoe is mounted on the support. The operator next depresses slightly the treadle 34, causing the roll 76 to engage the shoulder 82 of the arm 78 and thus to swing the jaw 24 into position to press the end portion of the sole upon the points of the coöperating gripping jaw comprising the pin 20. By the same movement of the treadle 34 the pawl 54 is released in the manner hereinbefore described and is permitted to engage the teeth 50 of the rod 40. The operator now forces the rod 40 forward by pushing against its handle end 44 to bring its forked end 42 into engagement with the last, and the rod is held in its advanced position by the pawl 54. It will be evident that the construction of the rod 40 whereby it is permitted to engage the last in any location between the bottom and the top of the heel portion renders it adaptable to the position of the last irrespective of the extent to which the last may have been forced into the shoe by the preliminary

hand operation. With the parts in this position, as represented in Fig. 1 of the drawings, further depression of the treadle 34 serves to force the last forward into the toe 5 end of the shoe as far as required. During this operation the last engaging end 42 of the rod 40, by reason of its relation to the axis 30 of the lever 28, describes a downward curve, and consequently the rear end of the 10 last receives a combined downward and forward movement. It will be apparent that the pressure applied to the last may be as gradual as desired, in order to avoid undue strain upon the shoe. After the last has 15 been partially forced into the shoe the operator may, if he desires, partially retract the lever 28 and force the rod 40 farther forward relatively to the lever in order to obtain a better leverage for the final stage of 20 the operation, the rod then engaging the last nearer the top of the heel portion. As the last is moved forward the jaws 20 and 24 by engagement with the sole restrain the shoe from forward movement. It will be 25 observed that the roll 76 is so positioned with reference to the axis 30 that during the operative movement of the lever 28 the roll approaches a position vertically over this axis and consequently operates upon the arm 30 78 to increase progressively the pressure upon the sole as the forcing pressure upon the last is increased during the more difficult latter portion of the last inserting operation. This arrangement insures that the shoe shall be effectually restrained at all 35 times from forward movement.

As the last is forced into the shoe the sole of the shoe is pressed against the pad 10, and this pressure may cause the shoe support 40 to swing slightly about the pivot 12 to accommodate the pad to the shape and position of the shoe. A pad of the shape and material described not only insures that the surface of the sole shall not be injured 45 under the pressure to which it is subjected, but also operates to a considerable extent to mold and shape the sole in the shank to the form required for the finished shoe, thus eliminating to some extent the necessity 50 for subsequent shaping operations upon the sole.

In order to adapt the machine for operation upon shoes having sewed heel seats, the gripping member 24 shown in Fig. 1 is removed from the supporting pivot 26, and a member 84 shown in Fig. 2 is substituted. This member has an arm 86 suitably curved to enter the shoe from the top and coöperate with the pin 22 in gripping the sole, and another arm 88 for engagement with the roll 76. In the idle position of the member 84 the arm 86 rests against the roll 76, as shown by full lines in Fig. 2, and while the member is in this position 65 the shoe is positioned upon its support with

the rear end of the shoe in engagement with the curved central portion of the member 84 which serves to determine the longitudinal position of the shoe. The member 84 is then turned by hand substantially to the 70 dotted line position, the arm 88 being short enough to clear the roll 76. The treadle is then depressed to cause the roll to engage the arm 88, and the subsequent operations are the same as described with reference 75 to the form shown in Fig. 1.

After the last has been forced into the forepart of the shoe in the manner described, the parts are returned to their initial positions immediately upon the release 80 of the treadle 34, leaving the shoe free to be removed from the machine. The insertion of the last in the shoe should then be completed by drawing the heel portion of the shoe over the last, an operation which 85 may be effected advantageously by the use of the machine which forms the subject-matter of my prior Patent No. 1,150,804, granted August 17, 1915.

Having described the invention, what I 90 claim as new and desire to secure by Letters Patent of the United States is:—

1. A machine of the class described having, in combination, shoe engaging means comprising a support for the bottom of a 95 shoe in the shank, means constructed to engage a last at the rear of the heel portion in any selected location between the bottom and the top of the last, and mechanism for relatively moving said shoe engaging means and last engaging means to cause the last to be inserted in the toe portion of the shoe. 100

2. A machine of the class described having, in combination, shoe engaging means comprising a support for the bottom of a 105 shoe in the shank, means constructed to engage a last at the rear of the heel portion on opposite sides to steady the last with freedom for relative movement between said means and the last to permit said means to 110 engage the last at different distances from the heel seat, and mechanism for relatively moving said shoe engaging means and last engaging means to cause the last to be inserted in the toe portion of the shoe. 115

3. A machine of the class described having, in combination, a shoe support, a forked member having diverging surfaces arranged to cause the heel end of a last partially inserted in a shoe on said support to 120 be wedged between them, and means for operating said member to force the last into the shoe.

4. A machine of the class described having, in combination, a support for the bottom of a shoe, means for gripping the heel end of the sole of the shoe, means constructed to engage a last at the rear of the heel portion in any selected location between the bottom and the top of the last, 130

and mechanism for relatively moving said gripping means and last engaging means to cause the last to be inserted in the toe portion of the shoe.

5. A machine of the class described having, in combination, a shoe support constructed to engage the bottom of a shoe, means for gripping the heel end of the sole of the shoe, last engaging means constructed to abut against the rear end portion of a last partially inserted in the shoe with freedom for relative movement between said means and the last to permit said means to engage the last at different distances from the heel seat, and mechanism for operating said last engaging means to force the last into the shoe.

6. A machine of the class described having, in combination, a shoe support, a last engaging member constructed to abut against the rear end portion of a last partially inserted in a shoe on said support, said member being mounted to swing about an axis below and at the rear of the shoe, and means for swinging said member about said axis to force the last forwardly and downwardly into the shoe.

7. A machine of the class described having, in combination, a shoe support, a lever pivoted to swing about an axis below and at the rear of said support, means carried by said lever for engaging the exterior surface of the heel end of a last partially inserted in a shoe on said support, and a treadle for operating said lever to force the last into the shoe.

8. A machine of the class described having, in combination, shoe retaining means, a member for engaging a last partially inserted in a shoe engaged by said means, and means for operating said member to force the last into the shoe, said member being movable relatively to its operating means to effect a preliminary engagement with the last.

9. A machine of the class described having, in combination, shoe retaining means, an operating member movable to force a last into a shoe engaged by said means, a last engaging member carried by said operating member and movable relatively thereto to effect a preliminary engagement with the last, and means for normally retracting said last engaging member relatively to the operating member to permit a last to be partially inserted in the shoe by hand.

10. A machine of the class described having, in combination, shoe retaining means, an operating member movable to force a last into a shoe engaged by said means, a last engaging member carried by said operating member and movable relatively thereto toward or from the last, means tending to retract said last engaging member while permitting it to be moved into engagement

with a last, and means for retaining the last engaging member in an advanced position relatively to its operating member during its operation upon a last.

11. A machine of the class described having, in combination, shoe retaining means, an operating member movable forwardly to force a last into a shoe engaged by said means, a last engaging member carried by said operating member and movable relatively thereto toward or from the last, means for retaining said last engaging member in an advanced position relatively to the operating member during its operation upon a last, and means for releasing said last engaging member to permit it to be retracted upon the return of the operating member to its idle position.

12. A machine of the class described having, in combination, shoe retaining means, an operating member movable forwardly to force a last into a shoe engaged by said means, a last engaging member carried by said operating member and movable relatively thereto toward or from the last, pawl and ratchet mechanism for retaining said last engaging member in different advanced positions relatively to the operating member, and means operated by the rearward movement of said operating member for withdrawing the pawl from the ratchet to permit the last engaging member to be retracted.

13. A machine of the class described having, in combination, shoe retaining means, a lever movable to force a last into a shoe engaged by said means, a pusher rod carried by said lever and movable relatively to the lever toward or from the last, a spring for normally retracting said rod, ratchet teeth on the rod, a pawl on the lever arranged to engage said teeth for retaining the rod in different advanced positions relatively to the lever, and means for withdrawing the pawl from said teeth when the lever is in its idle position and for rendering the pawl operative to engage the teeth at the beginning of the operative movement of the lever.

14. In a machine of the class described, the combination with means for operating on a shoe, of a heel engaging member comprising a slide having an end forked to embrace the heel of a last in the shoe, a support in which the slide is movable endwise, a spring arranged to hold the slide normally retracted while permitting it to be moved forwardly to engage the work in different positions, and means for locking the slide against retraction by the spring.

15. In a machine of the class described, the combination with means for operating on a shoe, of a heel engaging member comprising a slide having an end forked to embrace the heel of a last in the shoe, a support

- in which the slide is movable endwise, a spring arranged to hold the slide normally retracted while permitting it to be moved forwardly to engage the work in different positions, means for locking the slide against retraction by the spring, and automatic means for operating said locking means to release the slide.
16. A machine of the class described having, in combination, means for forcing a last into a shoe, and means constructed and arranged for operation at the beginning of the movement of said last forcing means for engaging the shoe to restrain it from forward movement.
17. A machine of the class described having, in combination, means for forcing a last into a shoe, and means controlled by the operation of said last forcing means for engaging the shoe to restrain it from forward movement.
18. A machine for inserting a last in a shoe having, in combination, means for gripping the shoe to restrain it from forward movement, and means for forcing a last forwardly in the shoe, said gripping means being constructed and arranged relatively to the last forcing means to cause it to grip the shoe at the beginning of the movement of the last forcing means.
19. A machine for inserting a last in a shoe having, in combination, means for engaging the last, means for gripping the shoe, and mechanism for operating the last engaging means constructed and arranged to close the gripping means on the shoe and then to effect movement of the last.
20. A machine for inserting a last in a shoe having, in combination, means for engaging the last, means for gripping the shoe, and mechanism for operating said last engaging means to force the last into the shoe, said gripping means having an operating member extending into the path of movement of said operating mechanism to cause the gripping means to close upon the shoe prior to movement of the last.
21. A machine of the class described having, in combination, means for gripping the rear portion of the sole of a shoe to restrain the shoe from forward movement, means for forcing a last forwardly in the shoe, and means arranged to be operated by said last forcing means for rendering the gripping means operative to hold the shoe.
22. A machine of the class described having, in combination, last engaging means movable to force a last forwardly in a shoe, and means for gripping the rear portion of the sole of the shoe with pressure increasing progressively during the operation of said last forcing means to restrain the shoe from forward movement.
23. A machine of the class described having, in combination, means for engaging a last to force it forwardly in a shoe, means for gripping the sole of the shoe to restrain the shoe from forward movement, and mechanism for operating said last engaging means constructed and arranged to close the gripping means on the sole with pressure increasing progressively during the movement of the last.
24. A machine of the class described having, in combination, means for forcing a last forwardly in a shoe, a stationary jaw and a movable jaw arranged to engage the rear portion of the sole of the shoe to restrain the shoe from forward movement, and means operated by said last forcing means for moving said movable jaw to grip the sole.
25. A machine of the class described having, in combination, a shoe support, means for forcing a last forwardly in a shoe on said support, a stationary gripping jaw positioned with reference to said support to engage the rear portion of the sole of the shoe on its lower face, a pivoted gripping jaw arranged to engage the upper face of the sole over said stationary jaw, and means operated by said last forcing means for moving said pivoted jaw to gripping position.
26. A machine of the class described having, in combination, a shoe support, a member movable to force a last forwardly in a shoe on said support, a stationary gripping jaw positioned with reference to said support to engage the rear portion of the sole of the shoe on its lower face, a pivoted gripping jaw arranged to engage the upper face of the sole over said stationary jaw, and means on said member for swinging said pivoted jaw to gripping position.
27. A machine of the class described having, in combination, a shoe support, means for forcing a last forwardly in a shoe on said support, a pair of jaws arranged with reference to said support to grip the rear portion of the sole of the shoe to restrain the shoe from forward movement, and means operated by said last forcing means for closing the jaws on the sole under pressure increasing progressively during the forward movement of the last.
28. A machine of the class described having, in combination, a shoe support, a pivoted lever movable to force a last forwardly in a shoe on said support, a stationary jaw and a movable jaw arranged to grip the rear portion of the sole of the shoe to restrain the shoe from forward movement, said pivoted jaw having an arm extending into proximity to the lever, and means on the lever for engaging said arm to swing the movable jaw to gripping position.
29. A machine of the class described having, in combination, a support for the bottom of a shoe, and means for forcing a last into a shoe on said support, the support being mounted with freedom for movement

laterally of the shoe to permit it to adjust itself to the position of the shoe during the relasting operation.

30. A machine of the class described having, in combination, a support shaped for engagement with the bottom of a shoe, and means for forcing a last into a shoe on said support, the support being pivoted for movement laterally of the shoe to permit it to adjust itself to the shoe.

31. A machine of the class described having, in combination, a support shaped for engagement with the shank portion of the sole of a shoe, means at the rear of said support for engaging the sole to position the shoe, and means for forcing a last into the shoe, said support being pivoted for movement laterally of the shoe to permit it to adjust itself to the shoe.

32. A machine of the class described having, in combination, shoe engaging means comprising a shoe support and means for gripping the rear end portion of the sole of a shoe, last engaging means constructed and arranged to abut against the exterior surface of the rear end portion of a last partially inserted in the shoe, and mechanism for effecting relative swinging movement of said shoe engaging means and last engaging means about an axis extending laterally of the shoe to seat the last in the toe portion of the shoe.

33. A machine of the class described having, in combination, shoe engaging means comprising a shoe support and means for gripping the rear end portion of the sole of a shoe, last engaging means comprising a forked member for abutting against the rear end portion of a last partially inserted in the shoe, and treadle mechanism for effecting relative movement of said shoe engaging means and last engaging means to seat the last in the toe portion of the shoe.

34. A machine of the class described having, in combination, means for positioning a shoe, a last engaging member, a lever having an arm arranged to be positioned at the rear of the heel end of a last partially inserted in the shoe positioned by said means and upon which said last engaging member is mounted, and means for operating said lever to force the last into the shoe.

35. A machine of the class described having, in combination, shoe positioning means, a bell-crank lever having an arm at the rear of the heel end of a shoe positioned by said means, means on said arm for engaging a last partially inserted in the shoe, and means connected to the other arm of said bell-crank for operating it to force the last into the shoe.

36. A machine of the class described having, in combination, shoe positioning means, a bell-crank lever having an arm at the rear of the heel end of a shoe positioned by said

means and another arm extending forwardly lengthwise of the shoe, a forked member on said first mentioned arm constructed and arranged to abut against the heel end of a last partially inserted in the shoe, and a treadle connected to said forwardly extending arm for operating the lever to force the last into the shoe.

37. A machine of the class described having, in combination, shoe positioning means, a bell-crank lever having an arm at the rear of the heel end of a shoe positioned by said means, a member on said arm constructed to abut against the rear end portion of a last partially inserted in the shoe, and means connected to the other arm of the bell crank for operating it to force the last into the shoe, the bell-crank being pivoted and arranged with reference to the shoe to cause said member to have a component of movement toward the toe end of the shoe and a component of movement toward the shoe bottom.

38. A machine of the class described having, in combination, means for engaging a shoe, last engaging means constructed to abut against the rear end portion of a last partially inserted in the shoe, and operating mechanism for effecting relative movement of said shoe engaging means and last engaging means to seat the last in the toe end of the shoe, the last engaging means being movable lengthwise of the shoe and relatively to said operating mechanism to effect a preliminary adjustment of said means to the last prior to the operation of said mechanism.

39. A machine of the class described having, in combination, means for engaging a shoe, means for engaging the rear end of a last partially inserted in the shoe, operating mechanism for effecting relative movement of said shoe engaging means and last engaging means to seat the last in the toe end of the shoe, the last engaging means being movable relatively to said operating mechanism in the direction of the toe end of the shoe to effect a preliminary adjustment of said means to the last, and means for retaining said last engaging means in its advanced position during the relasting operation.

40. A machine of the class described having, in combination, means for supporting a shoe with a last partially inserted therein, a member constructed to abut against the rear end portion of the last, means for operating said member to force the last into the shoe, the member being movable relatively to its operating means in the direction of the toe end of the shoe to effect a preliminary engagement with the last, and means for locking said member in its advanced position during its operation to force the last into the shoe.

41. A machine of the class described having, in combination, shoe engaging means, last engaging means, operating mechanism for effecting relative movement of said means to cause a last to be inserted in a shoe, and means arranged to be operated by said relative movement of the shoe engaging means and last engaging means for gripping the rear end portion of the sole of the shoe.
42. A machine of the class described having, in combination, a shoe support, means for engaging the rear end of a last partially inserted in a shoe on said support, said means being movable to force the last into the shoe, means for gripping the rear end portion of the sole of the shoe, a treadle, and connections between the treadle and said last engaging means and gripping means to cause both said means to be operated by movement of the treadle.
43. A machine of the class described having, in combination, a shoe support for engaging the bottom of a shoe, means for engaging a last partially inserted in the shoe, and mechanism for effecting relative movement of said support and means to seat the last in the toe portion of the shoe, said support being mounted with freedom for movement laterally of the shoe to permit it to adjust itself to the position of the shoe during the relasting operation.
44. A machine of the class described having, in combination, shoe engaging means comprising a support for the bottom of a shoe in which a last is partially inserted, means constructed to engage the exterior surface of the heel portion of the last in any selected location between the bottom and the top of the last, and mechanism for effecting relative movement of said shoe engaging means and last engaging means to cause the last to be forced into the shoe.
45. A machine of the class described having, in combination, means for engaging a shoe in which a last is partially inserted to restrain the shoe from forward movement, last engaging means having diverging surfaces arranged to cause the heel end portion of the last to be wedged between them, and mechanism for imparting operative movement to said last engaging means to force the last into the shoe.
46. A machine of the class described having, in combination, means for engaging a shoe in which a last is partially inserted to restrain the shoe from forward movement, last engaging means constructed to engage the exterior surface of the heel end portion of the last in any selected location between the bottom and the top of the last, said last engaging means being mounted to swing about an axis extending laterally of the shoe to force the last into the shoe, and means for imparting operative movement to said last engaging means.
47. A machine of the class described having, in combination, means for engaging a shoe in which a last is partially inserted to restrain the shoe from forward movement, and last engaging means constructed to abut against the exterior surface of the heel end portion of the last, said last engaging means being mounted for swinging movement about an axis extending laterally of the shoe at the rear of the shoe to force the last forwardly into the shoe.
48. A machine of the class described having, in combination, means for engaging a shoe in which a last is partially inserted to restrain the shoe from forward movement, last engaging means, mechanism for operating said last engaging means to force the last forwardly into the shoe, said last engaging means and its operating mechanism being relatively adjustable in directions lengthwise of the shoe, and means for retaining said last engaging means and operating mechanism in adjusted relation.
49. A machine of the class described having, in combination, means for engaging a shoe in which a last is partially inserted, means for engaging the last, mechanism for operating said last engaging means to force the last into the shoe, and a take-up device between said last engaging means and operating mechanism to permit said means to be operated by repeated movements of said mechanism in the same path.
50. A machine of the class described having, in combination, means for engaging a shoe in which a last is partially inserted, means for engaging the last, and treadle operated means for effecting relative movement of said shoe engaging means and last engaging means to cause the last to be forced into the shoe, said last engaging means being adjustable upon a retraction of the treadle at an intermediate stage in the operation to permit the operation to be completed by a second movement of the treadle in the same path.
51. A machine of the class described having, in combination, means for engaging a shoe in which a last is partially inserted, means for engaging the last, a support upon which said last engaging means is mounted with provision for relative adjustment of said means and its support in directions lengthwise of the shoe, and means for effecting relative movement of said support and the shoe engaging means to cause the last to be forced into the shoe.
52. A machine of the class described having, in combination, means for engaging a shoe in which a last is partially inserted to restrain the shoe from forward movement, a lever mounted to swing about an axis ex-

tending laterally of the shoe to force the last into the shoe, and a last engaging member carried by said lever and extending transversely thereof toward the last, said member 5 being adjustable relatively to the lever in directions toward or from the last and constructed to engage the exterior surface of the heel end portion of the last in any selected location between the bottom and the 10 top of the last.

53. A machine of the class described having, in combination, means for engaging a shoe in which a last is partially inserted to restrain the shoe from forward movement, a 15 lever movable to force the last into the shoe, a pusher rod carried by said lever and having means for engaging the exterior surface of the heel end portion of the last, said pusher rod being adjustable relatively to the 20 lever in directions toward or from the last, means for retaining said rod in adjusted position, and means for imparting operative movement to the lever.

54. A machine of the class described having, in combination, shoe engaging means comprising a shoe support and means for gripping the rear end portion of the sole of the shoe to restrain the shoe from movement 25 relatively to the support, means for engaging a last partially inserted in the shoe on said support, means for effecting relative movement of said shoe engaging means and last engaging means to cause the last to be forced into the shoe, and means arranged to 30 be rendered operative by said relative movement of the shoe engaging means and the 35

last engaging means to cause said gripping means to grip the sole.

55. A machine of the class described having, in combination, means for engaging a 40 last partially inserted in a shoe, means for gripping the rear end portion of the sole of the shoe, and mechanism for effecting relative movement of said last engaging means and gripping means to cause the last to be 45 forced into the shoe, the machine being constructed to permit the use of different gripping means for different shoes made respectively with sewed and with nailed heel seats. 50

56. A machine of the class described having, in combination, means for engaging a last partially inserted in a shoe, shoe engaging means comprising mechanism constructed to support pivotally one of a pair of interchangeable devices for gripping the soles of different shoes made respectively with sewed and with nailed heel seats, means for effecting relative movement of said last engaging means and shoe engaging means to 55 cause the last to be forced into the shoe, and means constructed to coöperate with either of said pair of interchangeable gripping devices during said relative movement of the last engaging means and the shoe engaging 60 means to cause said device to grip and hold the sole of the shoe. 65

In testimony whereof I have signed my name to this specification.

HANNAH ASHTON,
Executrix of the will of Orrell Ashton, deceased.

Copies of this patent may be obtained for five cents each, by addressing the "Commissioner of Patents, Washington, D. C."
